BASE FOR COLOR COPYING SCREENS

Franz Piller, Munich, Germany

Application May 29, 1936, Serial No. 82,621
In Germany June 4, 1935

2 Claims. (CL 95—81.5)

The bases employed for color copying screens consist mainly of a paper foil faced with a thin layer of metal serving to increase the brilliancy of the colored copy and to allow of the expansion of the paper without detriment to the film of metal. It is also part of the prior art to provide the metal film with one or more waterproof or reflective coats in order to eliminate detrimental chemical or other action between the metal, the screen colors and the photographic emulsion. In all such cases it has been the rule to choose the metal layer of exceeding thinness and to make the paper base several times as thick as the metal layer, the paper base thus forming a substantially independent body.

In practice it has been found that a base of the above described kind does not possess the absolutely necessary insensibility to exterior influences (temperature, humidity, etc.) required to ensure the permanency of the screen lines, because the thin metal film is not strong enough to resist the stresses acting on the much thicker paper base and therefore expands or contracts in the same measure as the latter.

The present invention refers to a base for color copying screens which is entirely independent of the elastic changes of form on the part of the other units of the screen, remaining entirely unchanged both before and especially during the printing or ruling of the screen, so that the screen lines cannot become distorted, thus ensuring perfect registration with the screened negative.

By way of an example, the invention is illustrated by the drawing in which the figure comprises a briefed vertical section through the device.

According to the present invention the screen base consists essentially of a metal foil 1 of a sufficiently hard material with a coefficient of expansion so small that it can be practically neglected, as is, for instance, the case with aluminium and combinations of aluminium with another material or materials. This metal foil acts as a carrier or base for all further layers 2, 3, 4, 5, 6 and 7 which may be arranged in the usual manner and number on the face or back of the foil.

The layers destined for the upper side or face of the foil may comprise, for instance, two different groups arranged between the metal foil 1 and the color screen system. One group serves as a coat for the metal and the second as a reflecting background. The provision of reflective protecting coatings (for instance, of white lacquer) on metal for photographic purposes is in itself a part of the prior art, but such cases

do not embrace color copying screens and refer to other purposes and other conditions.

According to the present invention the metal foil 1 is first coated with a water repellent substance 6, for instance, wax or other suitable material, which serves to prevent any reaction of the metal. If this substance 6 is of a dark color, it may be covered with a coating of white lacquer, (not shown), for instance, of cellulose lacquer or similar material, which will neutralize the dark tone of the first coating. If, however, the first coating 6 is of a sufficiently light shade of color, the second layer may be dispensed with as shown in the drawing. In any case the metallic reaction will be entirely eliminated.

The second group of layers is now arranged on the top of the first group, the first layer of this second group serving as reflective layer 2 and consists, for instance, of baryta gelatine; on this is arranged a layer of transparent lacquer 7 to prevent penetration of the ink or other medium used for ruling the color screen into the reflective layer. On this fourth (or third) layer the color screen system 3, consisting of lines or the like, is now printed and then this screen system coated 25 with emulsion 4.

The arrangement that each layer or each group of layers serves for a certain purpose makes it possible to permanently eliminate the detrimental reaction of metal, coloring matter and emulsion 30 on each other and thereby to ensure perfect and efficient operation of the screen. It is immaterial for the purposes of this invention how many single layers are employed for each group of layers; under certain conditions it may be possible 35 to employ a single layer in place of each group, or even in place of both groups.

A further layer, for instance, of thin paper 5 or other suitable material, may be arranged on the back of the metal foil, in order to hide the 40 bright metallic surface and to prevent the metallic noise ensuing when piling or handling the naked foils. But in all cases the resistance to distortion of the metal foil will be greater than the sum of all stresses of the individual layers, 45 so that these stresses will not be able to cause distortion (expansion or contraction) of the metal foil. Since these layers are very thin, a thickness of the metal foil of a few hundredths of a millimetre, for instance, of about $\frac{1}{100}$ ths mm., will as 50 a rule be found sufficient.

What I claim as my invention, is:

1. A foundation for a color copying screen comprising a sheet of metal foil, the metal of said foil having a low expansion coefficient, a moisture re- 55

pellent layer on one surface of said foil, a reflective layer superimposed upon said first layer, said foil having a strength greater than the total strength of said layers to prevent the expansion and contraction thereof, and a color line screen formed on the outer surface of said second layer.

2. A foundation for a color copying screen comprising a sheet of metal foil, the metal of said foil

having a low expansion coefficient, a moisture repellent layer on one surface of said foil, and a reflective layer superimposed upon said first layer, said foil having a strength greater than the total strength of said layers to prevent the expansion and contraction thereof.

FRANZ PILLER.
